UNITED STATES PATENT OFFICE.

EMIL LANGER, OF NEUSTADT-ON-THE-METTAU, AUSTRIA-HUNGARY, AS-
SIGNOR TO FELIX LEDERER, OF VIENNA IX, AUSTRIA-HUNGARY.

CIRCULAR-KNITTING MACHINE.

SPECIFICATION forming part of Letters Patent No. 761,385, dated May 31, 1904.

Application filed October 7, 1903. Serial No. 176,116. (No model.)

To all whom it may concern:

Be it known that I, EMIL LANGER, a subject of the Emperor of Germany, residing at Neustadt-on-the-Mettau, in the Province of Bohemia, in the Empire of Austria-Hungary, have invented certain new and useful Improvements in Circular-Knitting Machines for the Manufacture of Striped Fabrics; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

In manufacturing two-thread or striped looped fabrics by means of circular-knitting machines it is usual to use two guides alternately adjusted in such a manner that the threads of different color are alternately fed to the needles for a fixed period.

The object of this invention is to change the threads so that they will lap on a single needle only, no matter how many needles are arranged in the needle-cylinder.

According to the invention this is accomplished by making the guides movable in parallel lines side by side and acting positively and alternately. This may be attained, by way of example, by means of a rocking lever articulated to the guides and provided with an arm in which engages the pin of a single-armed lever arranged below the rocking lever. Both the rocking lever and the single-armed lever carry projections. While the guides are rotating round the needle-cylinder these projections abut alternately and at fixed times against an abutment which is movable into the plane of the projections, whereby the changing of the guides is positively effected.

By making the projection and the pin of the single-armed lever adjustable the thread-guide stroke can be regulated accurately, and the action of the guide is controlled by the usual pattern-chain.

The drawings accompanying this specification illustrate the device for changing the threads.

In the drawings, Figure is a side elevation

of the device with the upper part of a circular-knitting machine. Figs. 2 and 3 are plans and Fig. 4 is a front elevation of the device with the thread-guide ring.

As shown by Fig. 1, the thread-guide casing 1, wherein the two thread-guides are movable in parallel lines side by side, is fixed on a projection 4 of thread-guide ring 5. The guide and the guide-ring move, therefore, in the well-known manner, with the cam-cylinder 7 rotating with the needle-cylinder 6. By means of the links 8 the thread-guides 2 and 3 are connected to the rocking lever 11, which carries the projection 9 and is arranged on the thread-guide casing 1, so as to oscillate round the pin 10. Underneath the rocking lever a single-armed lever 13, Figs. 3 and 4, is pivoted at 12 on the thread-guide casing, said lever carrying at its front end a pin 14, which engages in one arm of the rocking lever. The lever 13 is also provided with a projection 15. The thread-guide 2 receives the thread 16 from a spool adjusted as usual, while the second guide 3 is supplied with the thread 17 from a centrally-arranged spool 18, Fig. 1, the carrier of which rotates with the cam-cylinder and with the thread-guides.

In the position shown in Figs. 1 and 2 the thread 16 is hooked into the needle 20, while the thread 17 is out of the reach of the needle and cannot be knitted. Now if the projection 9 of the rocking lever 11 is caused to move past a fixed abutment 21, alternately adjustable in the planes of the projections 9 and 15, while the guides are rotating in the direction of the arrow α , Figs. 2 and 3, the rocking lever is oscillated, whereby the guide 2 is pushed forward and the guide 3 is drawn back, so that the changing of the threads is accomplished. By the oscillation of the rocking lever the single-armed lever 13 is likewise shifted outward, whereby the projection 15 of this lever comes within the reach of the suitably-adjusted abutment 21 and the withdrawal—that is to say, the changing of the thread-guide—is again accomplished.

By making the thread-guide stroke adjustable the changing of the thread can take place at a single needle only; but the device may be

adjusted to overlap the threads on any desired number of needles. For this purpose the pin 14 is fixed on the front end of an auxiliary lever 22, which is pivoted intermediate its ends 5 on the stud 23 of the lever 13 and the rear end of which can be held fast in every position by a set-screw 24 on the lever 13. By shifting the lever 22 in one or the opposite direction the distance between the needle 20 and the 10 eye of the thread-guide 3 may be regulated. For the same purpose the projection 15 of the lever 13 is arranged so that it can be displaced and, whenever desired, fixed by means of a set-screw 25. Moreover, the motion of 15 the guides may be accelerated or retarded accordingly as the projection 15 on the lever 13 is drawn nearer to or farther from the pivot of this lever. For the purpose of moving the abutment 21 into the reach of the projections 9 and 15 this abutment is made as a disk 21, rotatable around a spindle 26, which is vertically movable and pressed down by a spring 27. The lower end of the spindle is connected by a link with the longer arm of a 20 double-armed lever 29, pivoted at 28 on the frame of the machine, while the shorter arm of the same is within the reach of two projections 30 and 31 of different height arranged in a well-known manner on a chain 32, laid on a 25 chain-wheel 33, which is rotated intermittently by the motor of the machine in any desired manner.

As soon as a long projection 30 bears upon the finger 34 of the lever 29 the abutment 21 30 is raised for a short time into the reach of the projection of the rocking lever 11, whereas by the action of a shorter projection 31 the lever 29 is shifted, but only to such an extent as is required to bring the abutment 21 into 35 the reach of the projection 15 of the single-armed lever 13.

The adjusted thread-guides remain in their respective positions in action until the next projection of the chain 32 actuates again the lever 29, the period of the changing of the 40 threads thus depending on the distance between the projections on the chain.

The adjusting device for changing the thread-guides acts so rapidly that the thread-guides changing takes place in a faultless and correct manner even at a very high speed of rotation of the knitting-machine.

I claim—

1. In an apparatus for changing the thread-guides in circular-knitting machines for manu-

facturing striped goods, the combination with two movable thread-guides, of a rocking lever, links connecting said thread-guides with the opposite ends of said lever, a single-armed lever pivoted at one end, a pin carried by the other end of said single-armed lever and engaging the rocking lever, both of said levers having lateral projections, an abutment, and means for throwing said abutment alternately into the path of said projections, substantially as 65 and for the purpose specified.

2. In an apparatus for changing the thread-guides in circular-knitting machines for manufacturing striped goods, the combination with two movable thread-guides, of a rocking lever, 70 links connecting said thread-guides with the opposite ends of said lever, a single-armed lever pivoted at one end, a pin carried by the other end of said single-armed lever and engaging one end of the rocking lever, both of said 75 levers having lateral projections, an abutment, means for throwing said abutment alternately into the path of said projections, and means for adjusting the said pin to either side of the longitudinal axis of the said single-armed lever, substantially as and for the purpose specified.

3. In an apparatus for changing the thread-guides in circular-knitting machines for manufacturing striped goods, the combination with 85 two horizontal, parallel and endwise-movable thread-guides, of a rocking lever, a single-armed lever, said levers being arranged in different horizontal planes, links connecting the opposite ends of the rocking lever respectively with said thread-guides, means connecting the other end of the single-armed lever with the corresponding end of the rocking lever, lateral projections on said levers, 90 an abutment, a lever of the third order for raising and lowering said abutment to alternately throw it into the path of said projections, a pattern-chain and projections of different sizes carried by said pattern-chain arranged successively to engage one end of said 95 last-named lever for raising and lowering the abutment, substantially as and for the purpose specified.

In testimony that I claim the foregoing as my invention I have signed my name in presence of two subscribing witnesses.

EMIL LANGER.
